(57) **CLAIM**

We claim the ornamental design for a vehicular front lamp assembly, as shown and described.

DESCRIPTION

FIG. 1 is a top perspective view from a centerline corner showing a vehicular front lamp assembly of our new design; FIG. 2 is a top perspective view thereof from a side corner; FIG. 3 is a top plan view thereof; FIG. 4 is a bottom plan view thereof; FIG. 5 is a front view thereof; FIG. 6 is a side view thereof; FIG. 7 is a rear view thereof; and, FIG. 8 is side view thereof, opposite FIG. 6. The broken lines are for illustrative purposes only and form no part of the claimed design.
